UNITED STATES PATENT OFFICE.

MELVILLE LIEBENTHAL AND SYLVESTER LIEBENTHAL, OF CLEVELAND, OHIO.

DESIGN FOR A BOTTLE.

No. 40,080.

Specification for Design.

Patented June 22, 1909.

Application filed April 22, 1909. Serial No. 491,646. Term of patent 7 years.

To all whom it may concern:

Be it known that we, MELVILLE LIEBENTHAL and SYLVESTER LIEBENTHAL, citizens of the United States, residing at Cleveland, in the county of Cuyahoga and State of Ohio, have invented a new, original, and ornamental Design for Bottles, of which the following is a specification, reference being had to the accompanying drawing, forming a part hereof.

The figure is a perspective view showing the design of the bottle.

We claim:

The ornamental design for a bottle as shown.

MELVILLE LIEBENTHAL.
SYLVESTER LIEBENTHAL.
